SHOE CHANNEL CEMENTING MACHINE

Joseph Barbati, Beverly, Mass., assignor to United
Shoe Machinery Corporation, Borough of
Flemington, N. J., a corporation of New Jersey

Application May 16, 1938, Serial No. 208,140

7 Claims. (Cl. 12—80)

This invention relates to machines for applying cement to the channel of a shoe in order to attach the chafinel flap to the sole. It is herein illustrated as embodied in a machine of the extrusion type in which the work is manually presented to a depending nozzle and moved to carry successive portions of the channel past the nozzle.

Channel-cementing machines of the extrusion type are being successfully employed for the application of cement to shoe channels through a depending, tapered, rigid nozzle. It will be understood, however, that the channel-forming knives employed in different styles of shoes and by different manufacturers are not uniform. Furthermore, the depth of the channel varies between the forepart and the shank portions of the shoe. For the correction of the first difficulty, a variety of nozzles is provided but shoe manufacturers are sometimes reluctant to stock a supply of differently shaped nozzles and frequently the operator is unwilling to take the time to change from one nozzle to another as the class of work varies. Channels of the so-called English type, having a curved base and as illustrated in Fig. 5 of Letters Patent of the United States No. 1,901,140, granted March 14, 1933, on the application of Arthur Bates, are difficult to coat properly with a rigid nozzle.

In order to meet these conditions and to provide a machine which may successfully be employed with a wide variety of shoes, my invention provides, in accordance with one feature thereof, a specially positioned and shaped drag brush for spreading the cement after it has been applied by a machine of this type. This brush, as illustrated, is pointed to enter the channel and is supported on the machine in position pointing downwardly and rearwardly in a direction opposed to the direction of movement of the work. As a consequence, the bristles are radically deflected during use and always spring back sufficiently to be operative in treating successive shoes, regardless of the tendency of the sticky cement to hold the bristles in their deflected position.

Another feature of the invention resides in the provision of a crease-entering guide finger by which the operator is enabled readily to hold the work in proper relation to the extruding nozzle. This finger is illustrated as yieldably supported for movement toward and away from the nozzle thereby to accommodate varying thicknesses of stock in the sole and associated welt. Furthermore, the pivoted support for the finger is yieldably urged toward the work and, hence, enables

the finger to accommodate itself to varying depths of crease between the upper and the welt.

These and other features of the invention will be described in the following specification, taken in connection with the accompanying drawings, 5

Fig. 1 is a side elevation of the machine with a portion of the frame removed to show the interior mechanism;

Fig. 2 is a detail angular view on a larger scale 10 of the crease-entering guide finger, showing the way in which it is supported;

Fig. 3 is an angular view on a much larger scale showing the nozzle and the drag brush;

Fig. 4 is another view of the support for the 15 drag brush, taken in the opposite direction from Fig. 3, and

Fig. 5 shows the action of the nozzle and brush in coating the channel of a shoe sole.

The invention is illustrated as embodied in a 20 machine of the type shown in Letters Patent of the United States No. 2,098,253, granted November 9, 1937, on an application of W. L. MacKenzie, for Channel cementing machines, but it will be clear that it may be embodied in other machines 25 having different coating mechanism. The machine comprises a hollow frame 10 mounted on a suitable pedestal 12 and is provided with an applying nozzle 14 to which cement is delivered, when permitted by a control valve 16, through a 30 flexible pipe 18 from a receptacle 20 under the pressure provided by a pump 22. This pump is driven by power imparted by a drive shaft 24 and the opening of the valve 16 is effected by a lever 26 operated indirectly, as described in the above- 35 mentioned patent, by a treadle rod 30 connected to a treadle (not shown) and adapted to be depressed to a position determined by the engagement of a pivoted arm 32 with a fixed stop 34. The machine is also provided with a flap-engaging finger 36 mounted for oscillation toward and away from the side of the nozzle 14 by a cam-actuated lever 38 under the control of a toggle mechanism 40 which is brought to the operative 40 position shown on depression of the treadle rod 45

It will be understood that shoes, held in inverted position, are presented to the nozzle 14 by the operator, who moves the shoes with respect to the nozzle to present successive portions of the 50 channel thereto. In so doing, it is important that the pointed lower end 42 of the nozzle be held at the root 44 (Fig. 5) of the channel of a shoe S. This positioning of the shoe is facilitated by a crease-entering guide finger 50 adapted to be in- 55

serted in the crease 52 (Fig. 1) between the upper and the sole or welt, as the case may be. This finger has a rounded thin end 54 and is pivotally mounted at 56 on an arm 60 arranged to swivel 5 on the drive shaft 24 to accommodate variations in the depth of welt crease. When the treadle is depressed, the arm 60 is swung toward the shoe by a link 62 connected to a bell crank 64, the end 66 of which is forked to surround the 10 treadle rod and is engaged by a washer 68 against which rests a spring 70 under compression. The weight of the arm 60 is supported by a spring 72 which, when the treadle is released, returns the arm to an inoperative position, away from the 15 work. It will be noted that the finger 50 is adjustable as to length by a screw-and-slot connection 74 and that it is yieldable up and down with respect to the nozzle to accommodate various thicknesses of the stock in the sole and/or welt 20 by reason of the pivotal mounting around the pin 58. Movement around this pin is controlled by a spring 76 and a stop screw 78.

The nozzle illustrated is of the construction shown in Figs. 9 and 10 of the above-mentioned 25 patent, being provided with a tapered end having a rounded rear edge 80 to facilitate movement of the work with respect to the nozzle. The nozzle is also provided with outlet slots, at its lower end, such as that shown at 84 for coating the inner 30 side of the flap F, and formed between the body of the nozzle and a removable plate 82 which, as the nozzle is positioned in the machine, is in a substantially vertical plane. The other outlet slot for coating the base B of the channel is not 35 shown in the drawing. It will be noted that this nozzle 14 is positioned in a depending relation to the machine and is inclined downwardly and forwardly with respect to the direction of movement of the work, as indicated by the arrow in Fig. 5. 40 The flap is held against one side of the nozzle by the oscillating finger 36 and the operator must hold the bed B of the channel against the other side of the nozzle. This he is enabled to do with greater facility with the assistance of the crease-entering guide finger 50 which is able to follow 45 variations in the thickness of the work and in the depth of the crease by reason of its mounting on the machine.

After the cement has been extruded from the 50 nozzle 14, it is spread by a drag brush 90, the bristles of which are trimmed to form a point 92. This brush is carried on an arm 94 which depends from the machine and is pointed downwardly and rearwardly in a direction opposed to 55 the direction of movement of the work. As a consequence, the engagement of the work with the brush deflects the bristles radically, as shown in Fig. 5, so that they are held in firm engagement with the various portions of the channel 60 and become more effective in spreading the cement. It has been found by trial that brushes mounted in other positions with respect to the nozzle do not spring back to the proper relation with respect to the nozzle after they have been 65 utilized for a comparatively short length of time and, as a consequence, they become ineffective. With my novel arrangement, however, the bristles are so radically deflected by engagement with the work that they readily spring back to their 70 original position, shown in Fig. 3, when a piece of work is withdrawn and, consequently, are equally effective on subsequent pieces of work. This is true regardless of the effect of the sticky cement tending to hold the bristles in their deflected position. The bristles are held within a

casing 96 having an upstanding shank 98 which is received within a recess in the arm 94 and held therein by a positioning pin 100 and a leaf spring 102. This arrangement, by allowing the brush to be deflected slightly, prevents jamming of the brush in the work and facilitates the presentation of the work to the machine. The shank 94 of the brush support may be adjusted vertically on a block 104 by a screw-and-slot connection 106 and the block 104, in turn, may be adjusted 10 horizontally on a subframe 15 by which the nozzle 14 and the flap-engaging finger 36 are carried, by a slot-and-screw connection 110. These two adjustments, therefore, enable the brush to be brought to just the desired position with respect to the nozzle and permit this position to be changed when the bristles become worn.

In the use of the machine, the work will be presented to the nozzle 14 with the flap F between the side of the nozzle and the finger 36. The 20 operator will then depress the treadle connected to the treadle rod 30, thereby bringing the guide finger 50 into the crease 52 of the shoe, starting the oscillation of the finger 36 and opening the valve 16, as described in the above-mentioned 25 patent. Movement of the shoe by the operator in the direction indicated by the arrow in Fig. 5 will cause successive portions of the channel to be presented to the nozzle and the deflected drag brush 90, thereby effecting a complete and uniform 30 form distribution of cement on the work.

Having described my invention, what I claim as new and desire to secure by Letters Patent of the United States is:

1. In a channel-cementing machine, a depending nozzle past which the work is moved progressively in a forward direction, means for extruding cement through said nozzle, and a spreading brush associated with the nozzle on the forward side thereof and pointed downwardly and rearwardly in a direction opposed to the direction of movement of the work. 35

2. In a channel-cementing machine, a tapered nozzle positioned on the machine to point downwardly and forwardly with respect to the direction of movement of the work presented progressively to the nozzle, means to extrude cement through the nozzle, a brush support on the machine, and a brush carried by said support pointed downwardly and rearwardly in a direction opposed to the direction of movement of the work and toward the forward side of the nozzle. 45

3. In a channel-cementing machine, a rigid nozzle having outlet slots, means for extruding cement through said nozzle upon work moved forwardly past the nozzle, said slots being positioned substantially vertically adjacent to the forward side at the end of the nozzle, and a pointed brush supported on the machine and inclined downwardly and inwardly toward that side of the nozzle farthest away from that side of the nozzle toward which the work approaches whereby the brush bristles will be radically deflected by contact with the work and will spread the cement applied by the nozzle over the whole 60 area of the channel. 55

4. In a channel-cementing machine, a rigid nozzle supported on the machine in depending position with an outlet near its lower end, means for extruding cement through said nozzle as a 70 piece of work is presented to it, a crease-entering work-guiding finger adjacent to said nozzle, and means for supporting said finger for movement downwardly away from the nozzle end. 75

5. In a channel-cementing machine, a rigid

5 nozzle supported on the machine, means for extruding cement through said nozzle, a crease-entering work-guiding finger, and means for supporting said finger for movement laterally of the nozzle to permit automatic adjustment of said finger, as the work advances, in accordance with the varying depth of the crease.

6. In a channel-cementing machine, a rigidly supported tapered nozzle, means for extruding 10 cement through the tapered portion of said nozzle, a work-guiding crease-entering finger, movable means for supporting said finger yieldably to permit automatic adjustment for variations in the thickness of the channeled sole, and operator-controlled means for yieldably moving said 15 movable supporting means toward the work.

7. In a channel-cementing machine, a tapered nozzle inclined downwardly and forwardly with respect to the direction of movement of the work, means including a control valve for extruding cement through said nozzle, a drag brush associated with the forward side of the nozzle and pointed downwardly and rearwardly with respect to the direction of movement of the work; a pivoted support, a work-guiding crease-entering finger yieldably mounted on said support, and operator-controlled means for urging said support toward the work and for opening said valve. 5 10 15
